DESIGN FOR A WRITING INSTRUMENT

Howard L. Fischer, St. Paul, Minn., assignor to
Brown & Bigelow, St. Paul, Minn., a corporation
of Minnesota

Application March 28, 1947, Serial No. 137,998

Term of patent 14 years

(Cl. D74—24)

To all whom it may concern:

Be it known that I, Howard L. Fischer, a citizen of the United States, residing in Saint Paul, county of Ramsey, and State of Minnesota, have invented a new, original, and ornamental Design for a Writing Instrument, for which the following is a specification, reference being had to the accompanying drawings, forming part thereof:

Fig. 1 is an elevational view of a writing instrument showing my new design with the point in writing position.

Fig. 2 is also an elevational view with the point out of writing position.

Fig. 3 is a top plan view of the disclosure in Fig. 2.

Fig. 4 is a top plan view of the disclosure in Fig. 1.

Fig. 5 is an enlarged end view thereof looking at the writing point.

I claim:

The ornamental design for a writing instrument, as shown.

HOWARD L. FISCHER.
